UNITED STATES PATENT OFFICE.

FRED C. SCHOENTHAL, OF BUFFALO, NEW YORK, ASSIGNOR, BY MESNE ASSIGNMENTS, TO STEEL WHEEL CORPORATION, OF LANSING, MICHIGAN, A CORPORATION OF MICHIGAN.

DISK WHEEL.

Original application filed August 23, 1919, Serial No. 319,396. Divided and this application filed August 26, 1921. Serial No. 495,692.

This application is a division of application Serial No. 319,396, filed August 23, 1919.

This invention relates to improvements in disk wheels, particularly in those of the reinforced single disk type.

One of the objects of my invention is to provide a disk wheel of a single plate disk concentrically bent to give the disk resiliency, and having a felloe portion at the periphery of the plate formed by bending the same to give a circumferential shoulder and foundation to the demountable wheel rim.

Another object is to provide a wheel and sectional rim, having the rim of simple construction and demountable and at the same time separable, using only bolts to hold the parts together and to the felloe.

Another object is to provide a single disk wheel, which will replace the present wood wheel on a given standard hub.

With these and other objects my invention resides in certain construction, one embodiment of which is illustrated in the drawings, as adapted to the present Ford type of hub and is hereinafter described and which I claim is set forth.

In the drawings,

Figure 1 is a fragmentary front elevation of a wheel embodying my invention.

Figure 2 is a section taken on the line X—X of Fig. 1.

Figure 3 is a plan of a clamping outside hub disk.

Figure 4 is a medial section of the clamp-hub disk shown in Figure 3.

Figure 5 is a plan of the backing plate formed to concentrically fit a hub and flange of the Ford type.

Figure 6 is a section of the backing plate shown in Figure 5.

Figure 7 is a perspective view of one of the reinforcing pieces which bridge the felloe at the bolt holes.

Figure 8 is a section of clincher rim to be used as an alternate form of rim to that shown in Figures 1 and 2.

In the figures, there is shown a hub 1 journaled upon a shaft 2. Mounted on the hub 1 is a backing plate 3, secured by three bolts 4, to the flange 5 of the hub 1. Positioned between pairs of bolts 4 are outstanding posts 6, integral with the plate

3. Mounted upon the hub 1, is the single bent disk 7, having a reinforcing plate 8, bent to lie in the annular groove 9, of the plate 3 and spaced at this point from the disk 7. The periphery 10, of the plate 8, is welded to the disk 7. The disk 7 is bent circumferentially towards the back of the wheel and then curves outward toward the front of the wheel in the plane thereof and has its peripheral zone formed into an angular felloe portion 11, the edge of which is conically bent outward to conform to the back of the rim ring 12.

To the rim ring 12, a rim ring 14 is secured by bolts 15, having nuts 16 which pass through holes 17 in the felloe portion 11.

Between the bolts 15, are bolts 18 passing through the flanges 19 of the rim rings 12 and 14, and through holes 20, in the felloe portion 11, which holes are not large enough to allow the heads 21 to pass, so that the rim rings 12 and 14 are clamped as one 75 piece to the felloe portion 11.

The felloe portion 11 is reinforced about the bolt holes by bridging pieces 22, which are welded in place. The heads 21 are held from turning by means of cotter pins 21 80 passing through the bridging pieces 22.

The disk 7, is secured to the backing plate 3, by means of nuts 4^a, threaded on the studs 6^a, secured in the post 6, the nuts 4^a bear against the plate 3^a, in pockets 3^b, and cause the plate 3^a to clamp the disk 7 against the backing plate 3.

Radially fixed in the felloe portion 11, is the tire valve tube 23.

It will be noticed that the bend 7^a, of the disk 7 permits of the inner end of the tube 23, being exposed on the outside of the wheel.

The clincher rim 12^a, shown in Figure 8, has an inturned flange 19^a, similar to the flange 19, of the separable rim shown in Figure 2. The rim 12^a with its flange 19^a is adapted to fit upon the felloe portion 11, of the wheel. In this case one set of bolts 18^b and nuts are required to hold the rim 100 upon the felloe.

While the wheel above described and illustrated is designed to be detachably mounted upon a Ford type of hub, changes in its construction can be made to adapt 105 the same to other types of hubs without de-

parting from the spirit and scope of my invention; I therefore do not wish to be confined to the one embodiment herein illustrated and described.

5 Having described my invention I claim:

In a disk wheel comprising a hub, a single sheet metal disk on said hub having its

periphery formed into a felloe portion having bolt holes adapted to receive bolts fixing a rim thereon, and reinforcing pieces 10 bridging an annular recess in said felloe portion at said holes.

In testimony whereof I affix my signature.

FRED C. SCHOENTHAL.
